PACKAGE OF WRAPPED PIECES OF
CHEWING GUM OR THE LIKELawrence Saladin and Willet B. Ranney, Chicago,
Ill., assignors to Wm. Wrigley Jr. Company,
Chicago, Ill., a corporation of Delaware

Application September 25, 1939, Serial No. 296,378

7 Claims. (Cl. 206—56)

This invention relates to a novel and improved package of wrapped pieces of chewing gum, candy, or the like, and consists of the matters hereinafter described and more particularly pointed out in the appended claims.

The object of the invention is to provide a novel and improved flat package of wrapped pieces disposed edge to edge in a common plane, with a sealed package wrap of one sheet enclosing said pieces capable of being readily opened at one end to remove the pieces one at a time, without disturbing the remaining pieces.

Another object of the invention is to provide a package of the kind with sealing flaps at one end of the wrapper sheet constructed to be readily grasped and pulled apart to break the seal and open the package.

These and other advantages of the improved package will appear more fully as we proceed with the specification.

In the drawings:

Figure 1 is a perspective view of the improved package with the wrapped pieces enclosed and sealed therein.

Figure 2 is a view representing an edge elevation of the package.

Figure 3 is a view representing a section through the package in a plane indicated by line 3—3 of Figure 1.

Figure 4 is a view representing, on an enlarged scale, a transverse section through the package in a plane indicated by the line 4—4 of Figure 1.

Figure 5 is a perspective view of one of the wrapped pieces of gum or the like to be enclosed in the package.

Figure 6 is a plan view showing the wrapper sheet laid flat with the wrapped pieces of gum or the like disposed on one section of the wrapper in manner as when enclosed in the wrapper.

Figure 7 is a perspective view of the package after the seal between the sealing flaps has been broken and one section of said wrapper sheet has been folded back to remove the first stick enclosed therein.

Figures 8 and 9 are plan views of one end of the wrapper sheet when folded upon itself, showing modified forms for ready grasping of the sealing flaps to pull them apart to break the end seal of the package.

Figure 10 is a perspective view of a modified form of wrapped pieces of gum or the like, to be enclosed in the package.

Figure 11 is a perspective view of one end of the package partially open to show the manner

in which the modified form of wrapped stick is enclosed in the package wrapper.

Referring now to that embodiment of the invention illustrated in the drawings, and particularly that shown in Figures 1 to 7 inclusive: 10 indicates the package wrapper sheet. It consists of an elongated strip of paper or other suitable material bent upon itself about a transverse line midway between its ends to provide sections 11 and 12, thus integrally enclosing one end 10a of the package. 13 indicates the several wrapped pieces 13a of gum or the like, in this case five, enclosed by the wrapper sheet.

Each piece 13a is enclosed by a flat tubular wrapper 14 overlapped and sealed along a line 15 running longitudinally of the piece with its ends extended beyond the ends of the piece and sealed together to provide flat end fins 16. Said fins are located in a median plane between the top and bottom faces of the pieces and have lateral margins 16a which project somewhat beyond the planes of the lateral edges 14a of the tubular wrapper 14. The wrapper 10 is of a width to provide lateral marginal sealing flaps 11a, 12a to be folded down against the ends of the wrapped sticks 13 and to embrace and seal between them the end fins 16 of the wrapped pieces 13.

In the package wrapper sheet 10 the wrapped pieces 13 are arranged transversely of said sheet in a row extending longitudinally of the wrapper 10. The end fins 16 of the wrapped pieces 13 are engaged and sealed between said lateral marginal flaps 11a, 12a of the two sections 11 and 12 of the wrapper, with the proximate lateral margins 16a of the fins 16 of adjacent sticks disposed in overlapping relation, as indicated in Figure 6.

The sections 11, 12 of the wrapper project beyond the last piece at that end of the package and are formed to present preferably triangular combination sealing and opening flaps 17. Said flaps are provided adjacent the said last piece with opposed bands 17a bearing a sealing medium by means of which the two flaps may be sealed together to close the proximate end of the package.

Beyond said sealing band the flaps 17 are free and unsealed, to be engaged by the fingers to pull one flap from the other flap to break the seal at the proximate end of the package and between the lateral sealing marginal flaps 11a, 12a of the wrapper to release the first wrapped piece 13. Said piece may be then removed without disturbing the remaining pieces which are left sealed within the package, the sealing flaps of which may be again brought together and

sealed or folded down upon the package against the margin of the next wrapped piece 13. This may be continued until all of the wrapped pieces have been used. It is obvious that the pieces left in the package will be retained and held in substantially the same manner as when the package is full.

By reason of the sealed engagement of the fin ends 16 of the wrapped pieces between the lateral marginal sealing flaps 11^a, 12^a of the wrapper, the five pieces of gum or the like are held in a common plane with sufficient rigidity to maintain the shape of the package. And the overlapping disposal of the lateral marginal projections 16^a of the fins 16 adds to that rigidity.

In that embodiment of the invention hereinbefore described, the flaps 17 are angular and overlapping throughout, with the apex of the angle in a longitudinal median line of the package. In said form the said flaps may become adhered together, and some difficulty may be encountered in grasping them to pull them apart to break the seal.

In the modification shown in Figure 8, the two flaps 17^a are formed at the ends with right angular notches 18, 18, with the notch in one flap opening through its right-hand edge, and the notch in the other flap opening through the left-hand edge. This results in non-overlapping parts or points 19, 19 to be gripped when pulling the flaps 17^a apart to break the seal. Obviously there is no chance of said parts or points 19 becoming adhered together, since they are offset, the one from the other.

In Figure 9 a somewhat different construction is shown. In this case the flaps 17^b are formed at the ends with notches 18^a, 18^a of an obtuse angle, with the notch in one flap opening through its right-hand edge, and the notch in the other flap opening through its left-hand edge. This results in non-overlapping, laterally spaced parts or points 19^a, 19^a which may be readily grasped and pulled apart to break the seal.

In Figure 10 is shown a modified form of the wrapped piece of gum to be enclosed in the package wrapper. In this case the piece is enclosed in a flat tubular wrapper 14^x as before, with its ends extended beyond the piece and squeezed together to provide flat end fins 16^x, 16^x. But said fins are folded back upon the body of the wrapper as shown in Figure 2. The wrapped sticks 13^x are disposed transversely of the wrapper sheet in a row extending longitudinally of the wrapper sheet as before. But their ends terminate short of the marginal sealing flaps 11^y, 12^y which are sealed directly together against the ends of the wrapped pieces.

We claim as our invention:

1. A package of pieces, comprising a wrapper made of an elongated sheet bent transversely upon itself to close one end of the package and form opposed sections, a plurality of pieces shorter in length than the width of the wrapper, each piece being enclosed in a tubular wrap having its ends sealed together to provide projecting end fins, said wrapped pieces being disposed edge to edge in a common plane transversely of the wrapper between the opposed sections thereof, said wrapper sections having lateral sealing margins between which said end fins are engaged, and having projecting end flaps sealed together against the edge of the proximate wrapped piece, leaving said flaps free beyond said seal.

2. A package of pieces, comprising a wrapper made of an elongated sheet bent transversely upon itself to close one end of the package and

itself to close one end of the package and form opposed sections, a plurality of pieces shorter in length than the width of the wrapper, each piece being enclosed in a tubular wrap having its ends sealed together to provide projecting end fins, said wrapped pieces being disposed edge to edge in a common plane transversely of the wrapper between the opposed sections thereof, said wrapper sections having lateral sealing margins between which said end fins are engaged, and having projecting end flaps sealed together against the edge of the proximate wrapped piece, said flaps being angular in form and being free of each other beyond said seal.

3. A package of pieces, comprising a wrapper made of an elongated sheet bent transversely upon itself to close one end of the package and form opposed sections, a plurality of pieces shorter in length than the width of the wrapper, each piece being enclosed in a tubular wrap having its ends sealed together to provide projecting end fins, said wrapped pieces being disposed edge to edge in a common plane transversely of the wrapper between the opposed sections thereof, said wrapper sections having lateral sealing margins between which said end fins are engaged, and having projecting end flaps sealed together against the edge of the proximate wrapped piece, said end flaps being free of each other beyond the seal and being formed with laterally offset, non-overlapping parts to be grasped when pulling them apart to break said seal.

4. A package of pieces, comprising a wrapper made of an elongated sheet bent transversely upon itself to close one end of the package and form opposed sections, a plurality of pieces shorter in length than the width of the wrapper, each piece being enclosed in a tubular wrap having its ends sealed together to provide projecting end fins having lateral projections, said wrapped pieces being disposed edge to edge in a common plane transversely of the wrapper between the opposed sections thereof, with the lateral projections of the end fins of adjacent wrapped pieces disposed in overlapping relation, said wrapper sections having lateral sealing margins between which said end fins are engaged, and having projecting end flaps sealed together against the edge of the proximate wrapped piece, leaving said flaps free beyond the seal.

5. A package of pieces, comprising a wrapper made of an elongated sheet bent transversely upon itself to close one end of the package and form opposed sections, a plurality of pieces shorter in length than the width of the wrapper, each piece being enclosed in a tubular wrap having its ends sealed together to provide projecting end fins having lateral projections, said wrapped pieces being disposed edge to edge in a common plane transversely of the wrapper between the opposed sections thereof, with the lateral projections of the end fins of adjacent wrapped pieces disposed in overlapping relation, said wrapper sections having lateral sealing margins between which said end fins are engaged, and having projecting end flaps sealed together against the edge of the proximate wrapped piece, said flaps being angular in form and being free of each other beyond said seal.

6. A package of pieces, comprising a wrapper made of an elongated sheet bent transversely upon itself to close one end of the package and form opposed sections, a plurality of pieces shorter in length than the width of the wrapper, each piece being enclosed in a tubular wrap having

its ends sealed together to provide projecting end fins having lateral projections, said wrapped pieces being disposed edge to edge in a common plane transversely of the wrapper between the opposed sections thereof, with the lateral projections of the end fins of adjacent wrapped pieces disposed in overlapping relation, said wrapper sections having lateral sealing margins between which said end fins are engaged, and having projecting end flaps sealed together against the edge of the proximate wrapped piece, said end flaps being free of each other beyond the seal and being formed with laterally offset, non-overlapping parts to be grasped when pulling them apart to break said seal.

7. A package of pieces, comprising a wrapper

of elongated opposed sections, a plurality of pieces shorter in length than the width of said opposed sections, each piece being enclosed in a tubular wrap, having its ends sealed together to provide projecting end fins, said wrapped pieces being disposed edge to edge in a common plane transversely of the wrapper between said opposed sections thereof, said wrapper sections having lateral sealing margins between which said end fins are engaged and having projecting end flaps sealed together against the edge of the proximate wrapped piece, leaving said flaps free beyond the seal.
